UNITED STATES PATENT OFFICE.

ARTHUR C. WARD, OF OAKMONT, PENNSYLVANIA, ASSIGNOR TO THE AUTOCAR COMPANY, OF ARDMORE, PENNSYLVANIA, A CORPORATION OF PENNSYLVANIA.

ADJUSTABLE OIL BURNER.

Application filed April 21, 1923. Serial No. 633,596.

My invention relates to oil burners intended for feeding oil for heating purposes, particularly for furnace use.

The main purpose of my invention is to secure coincident air and oil admission and control with adjustment of the relative openings and absolute cut-off for the oil.

A further purpose is to secure accessibility for cleaning purposes with or without coincident opening of the air and oil inlet passages.

A further purpose is to obtain cut-off for the oil with quick opening to a predetermined point and slow opening beyond this point along with coincident air control, preferably adjustable as to its closing position.

Further purposes will appear in the specification and in the claims.

I have preferred to illustrate my invention by but one form, selecting a form which has proved to be highly practicable, efficient and reliable and which at the same time well illustrates the principles of my invention.

Figure 1 is a longitudinal section of the preferred form of my invention.

Figure 2 is a rear end elevation of the structure seen in Figure 1.

Figure 3 is a section taken upon line 3—3 of Figure 1.

Figure 4 is a longitudinal section of the nozzle and adjoining air valve parts.

In the drawings similar numerals indicate like parts.

In the operation of oil burners the difficulty met in securing smooth and uniform flow of properly proportioned air and oil has been complicated by the clogging of the oil within the burner passages and by the consequent inclination of the operator to independently adjust the air and oil with a view to improving the burning qualities. When clogging takes place instead of cleaning the burner the operator disturbs the adjustment.

This practice of altering the set proportion of the openings is made more general by the fact that no satisfactory common control of air and oil has been available which is adapted to be set to a predetermined proportion and which is readily enough cleaned not to invite alteration of the setting in lieu of cleaning of the burner. My invention has been directed, therefore, toward remedying these defects and improving the individual

parts and relative adjustments of the burner. 55

The casing of the burner shown comprises a body 5 and a bonnet 6 secured through flanges 7 and 8 by bolts 9. A pin 10 insures accurate angular placing of the parts so as to maintain the angular relation desired—ordinarily parallelism—of the air and oil inlets 11 and 12. To improve the joint and at the same time to insure quick and accurate alignment of the body and bonnet, the body is recessed to receive the 65 circular flange 13 of the bonnet.

The stem 14 extends through the axis of the body and bonnet and is longitudinally bored at 15 to uniform diameter so as to supply a passage for the oil from the point 70 of oil inlet and to make this oil passage accessible for a cleaning wire entering from the outer end, which end is normally closed by plug 16.

At the inner end (the left end in Figure 75 1) this spindle carries an integral air valve 17 and a removable nipple 18. The nipple opening 19 forms a nozzle whose diameter will be selected to suit the duty for which the particular burner is intended, depending upon the viscosity of the oil intended to be used as well as upon other factors. The nipple is threaded into the stem—or, as here, into the valve upon the stem—at 20 and the rear of the interior of the nipple is belled at 80 85 21 to guide the cleaning wire easily into the nipple.

The air inlet 11 leads into the air chamber 22 and is shown as threaded at 23 for connection of the air pipe. The air chamber surrounds the rear end of the air valve. The face 24 of the air valve is tapered to cooperate with a tapered valve seat 25 within a sleeve 26 threaded at 27 into the front end of the body. The sleeve is adjustable 90 axially along the threads to vary the position at which the air valve "closes." It may be threaded into place tightly enough to stay in adjusted position or may be locked in adjusted position by any other suitable means. Openings 28 for a spanner wrench are shown.

The oil inlet 12 leads into the oil chamber 29, surrounding a cut-off oil closure 30 whose face 31 seats in closed position against 105 the body. In the illustration this seat is shown at the bottom 32 of a recess 33 of somewhat larger diameter than that of the

cut-off valve, with the purpose and intent that the oil shall be permitted to flow freely between the face of the cut-off valve and its seat as soon as the cut-off valve is lifted and in proportion to the extent of lifting of the valve. The total flow however, is not proportionate to the extent of this valve opening except as the same amount of movement is given to the stem permitting flow of oil through slots hereinafter described. The flat valve and seat at this point offer the advantage as compared with a tapered valve here of opening more fully for the same extent of spindle movement.

The cut-off valve is mounted upon a thread 34 cut upon the spindle and extending beyond the cut-off valve in both directions so as to provide for the adjustment of this valve axially of the spindle. The end of the valve is fitted at 35 to receive a wrench and the valve is locked in adjusted position by a lock nut 36. Obviously the valve need not have its seat recessed.

The quantity of oil fed when the cut-off valve is opened is controlled by varying the length which is uncovered of a slot or slots 37 in a cylindrical portion 38 of the stem, which cylindrical portion bears against the inner wall of a bore 39 within the body. The wall of the bore prevents access of oil to the slot or slots except for an initial access which I prefer to provide, immediately upon opening of the cut-off valve, through a counterbore 40 and for such additional exposure of the slot or slots as is caused by axial movement of the stem.

The cylindrical portion of the stem is thus initially "open" from the exterior to the bore throughout the length of the slot opening or openings but the cut-off valve may be adjusted to lie over the opening or openings to reduce their length and, in the closed position of the parts, all or a large part of the length of the opening or openings is closed by the wall of the bore in the body of the valve.

The bore 39 is larger in diameter than the thread 34 to permit assemblage of the stem within the body by insertion from left to right, prior to placing of the sleeve 26 carrying the air valve seat.

In order to keep the burner cool when in position before a hot furnace but not in use, I prefer to allow a little air leakage when the air valve is "closed", i. e., in its most nearly closed position. This slightly open air valve position is intended to be shown in Figure 1. A valve is provided in the air supply for complete closure.

Movement of the spindle to open both the air valve and the cut-off valve concurrently is provided by a thread 41 upon the spindle engaging within a corresponding thread in the bonnet and by a hand wheel 42 secured

43. The thread 41 must permit passage of the cut-off valve and nut either by registering with their threads or by reason of smaller diameter. The cap 44 tightens packing 45 about the stem.

70 The valve is usually mounted by means of the air supply pipe.

In assemblage, the nipple is mounted within the spindle and the spindle is inserted from the left end of the body before the bonnet is put in place. The air valve seat may then be inserted within the body to approximate position or, if the entire adjustment is contemplated by shifting the cut-off valve, to final position. The cut-off valve and lock nuts are mounted upon the spindle and adjustment is made by the cut-off valve position or by the position of the air valve seat or both so that the air valve and cut-off valve may seat concurrently, with 80 air leakage, is intended.

85 The bonnet is next applied. It may be turned to position if the pin 10 is to be subsequently applied or the spindle may be turned to permit the bonnet to come down home if the pin be already in the bonnet. The bonnet is then secured to the body by the bolts and the gland and hand wheel are applied.

90 Constant air leakage when the air valve is "closed" forms one of several possible reasons for quick initial oil valve opening such as is provided by counterbore 40.

95 The size of the slot, number of slots, the pressure of the air and oil and the taper of the air valve contact with its seat determine the proportion of air and oil for any intended standard opening and may be designed or may be determined experimentally to give the best results for any particular installation.

100 After the air and oil connections have been made the handle is turned to open the air valve and oil cut-off together and to concurrently expose the desired length of slot or slots for the air and fuel feed intended. Both valves are thus opened together and are preferably opened quickly to the predetermined extent of opening at which the burner is intended to operate. The oil is furnished at a pressure high enough to spray it through the nozzle. Five pounds has been found sufficient for this purpose.

105 Where the counterbore 40 is provided about the slot or slots, lifting of the cut-off valve gives immediate oil feed throughout a length of slot or slots slightly in excess of the axial length of counterbore to provide a slight excess of oil at the first opening. As the longitudinal movement of the spindle is increased, the increase of slot opening is proportionate to the increase of longitudinal movement of the spindle.

115 Though the burners are adjusted for a definite proportion of air and oil at a given

preferably maximum valve opening, by the construction shown they may be designed to secure any approximation which may be desired to the same mixture, representing any proportion of oil and air flow at intermediate valve openings as compared with the maximum capacity of the burner.

Different nozzles may be substituted at any time and the ultimate length of slot or slots available for exposure with full opening may be varied after initial setting and after use by advancing or retracting the cut-off valve position upon the spindle and correspondingly retracting or advancing the sleeve upon which the air valve seat is mounted. Since the cut-off valve is mounted so as to extend over the rear end of the open portion this shifting of the cut-off valve will leave a shorter or longer length of opening lying within the bore (and counterbore if there be a counterbore) to be exposed by valve-opening movement of the spindle.

When any clogging takes place the valves are closed and the plug is removed. A wire can then be run through the length of the stem and nipple and, if needed, an air pipe or water pipe for air or hot water can be attached to thoroughly cleanse the passage.

In view of my disclosure herein it will be obvious that other forms will occur to those skilled in the art securing all or a part of the benefit of my invention and it is my purpose to protect herein all such as fall within the reasonable spirit and scope of my invention.

Having thus described my invention, what I claim as new and desire to secure by Letters Patent is:—

1. In an oil burner, a hollow body, an adjustable valve seat within the body having lateral oil openings, a hollow spindle extending longitudinally of the body, a tapered valve carried by the spindle and engaging the seat, an air inlet to the body supplying air about the valve, a portion of the body being bored to fit the surface of the spindle and in closed positions of the valve to shut off lateral access to oil openings leading into the interior of the spindle, a cut-off valve adjustable in position to expose varying lengths of these openings, an oil inlet permitting flow of oil about the cut-off valve and means for moving the spindle axially to open the air valve and cut-off valve and expose the openings concurrently.

2. In an oil burner, a hollow spindle at an intermediate point threaded and having a portion between the thread and one end of uniform diameter provided with an opening for oil inlet to the interior, a casing for the spindle bored to fit the intermediate portion of uniform diameter and in one position of the spindle to overlie the opening and engage the surface about it and counterbored about the opening at one end where it overlies a portion of the opening, a valve seat

about the counterbore, a cut-off valve mounted upon the spindle to engage said seat, an oil inlet to admit oil about the cut-off valve, an air valve mounted upon the spindle, an air valve seat therefor mounted upon the casing, an inlet connection for air about the air valve and means for moving the spindle axially.

3. In an oil burner, a hollow spindle threaded near one end and having an intermediate portion of uniform diameter open for oil inlet to the interior, a casing for the spindle bored to fit the intermediate portion of uniform diameter to overlie the open portion and fit the surface about it, a valve seat adjacent the bored portion, a cut-off valve mounted adjustably upon the thread to engage said seat, an inlet connection for admitting oil about the cut-off valve, an air valve mounted upon the spindle, an air valve seat therefor, inlet connection for air about the air valve and means for moving the spindle axially.

4. In an oil burner, a hollow spindle threaded near one end and having an intermediate portion of uniform diameter open for oil inlet to the interior, a casing for the spindle bored to fit the intermediate portion of uniform diameter to overlie the open portion and to engage the surface about it, a valve seat adjacent the bored portion, a cut-off valve mounted upon the spindle to engage said seat, an inlet oil pressure connection about the cut-off valve, an air valve mounted upon the spindle, an air valve seat therefor upon the casing, the cut-off valve being adjustable relatively to the spindle, an inlet connection for air about the air valve and means engaging the thread by which the spindle may be moved axially.

5. In an oil burner a hollow spindle threaded near one end and slotted at an intermediate point to permit oil access from the side, a valve at one end of the spindle, a valve about the slitting adjustable to cover variant extents of the slitting and a casing about the spindle having seats for both valves.

6. In an oil burner, a casing having an open discharge end and an intermediate bore of uniform diameter, and a counterbore, an adjustable valve seat in the discharge end, a hollow spindle having an intermediate portion of uniform diameter to fit the bore of the casing open to the interior of the spindle, an air valve adapted to engage the seat in the casing, a cut-off valve seat upon the casing adjacent the uniform bore of the casing and at the end thereof farthest from the air valve, a cut-off valve mounted upon the spindle, adjustable upon the spindle to cover variant extents of the opening to the interior of the spindle, and means for giving longitudinal movement to the spindle to operate both valves concurrently.

7. In an oil burner, a casing open at one

- end and having a bore and counterbore, a hollow stem in the body fitting the bore and open longitudinally to the center where it fits the bore and at the counterbore to expose free from the bore an initial opening and differing additional lengths of opening with different positions of the stem, air and oil pressure connections about the stem, valve seats supported by the body, an air valve at one end of the stem and a cut-off valve upon the stem between the apertured portion thereof and the oil inlet. 25
8. In an oil burner, a casing having a cylindrical bore, a hollow spindle having a portion engaging the bore and slotted in said portion through to the hollow of the spindle, means for moving the spindle air and oil pressure connections for the casing at opposite ends of said bore, air inlet and 30 oil cut-off valves mounted upon the spindle and spaced by said bore, the oil valve being closely adjacent to the slot, and seats for said valves carried by the casing, each valve and
9. In an oil burner, a casing, a stem longitudinally movable and three valves cooperating between said casing and stem, one an air inlet valve, another an oil inlet valve and the third a cut-off valve for stopping flow 35 of oil completely adjustable to vary the extent of maximum opening of the oil inlet valve independently of the movement of the stem. 40
10. In an oil burner, an axially bored casing having an air valve seat at one end and an axially facing oil valve seat intermediate its length, in combination with a laterally apertured spindle fitting the casing to cover the apertures to varying degrees, an air valve upon the spindle and an oil valve adjustably mounted upon the spindle to co-operate with the seat and cover the apertures to differing extents. 45

ARTHUR C. WARD.
